UNITED STATES PATENT OFFICE.

OSCAR C. BAER AND ROBERT L. WHEAT, OF CHICAGO, ILLINOIS.

APPARATUS FOR MELTING WAX.

Original application filed March 26, 1923, Serial No. 627,550. Divided and this application filed September 22, 1923. Serial No. 664,319.

To all whom it may concern:

Be it known that we, OSCAR C. BAER and ROBERT L. WHEAT, citizens of the United States, and residents of the city of Chicago, county of Cook, and State of Illinois, respectively, have invented certain new and useful Improvements in an Apparatus for Melting Wax, of which the following is a specification.

10 Our invention relates to improvements in an apparatus for melting wax, and has for an object to provide such an apparatus with a heating platform or top plate on which a wax impression of a printer's plate can be placed; and to provide means for evenly heating said plate so that the wax can be readily removed from the copper impression of the plate by melting the same; and also to provide means on said apparatus for 15 draining the melted wax from the table into a particular receptacle.

Other objects will appear hereinafter.

This is a division of application, Serial No. 627,550, filed by applicants on March 25, 1923.

The invention consists in the combinations and arrangements of parts hereinafter described and claimed.

The invention will be best understood by 30 reference to the accompanying drawing forming a part of this specification, and in which—

Fig. 1 is a sectional view of a melting apparatus embodying the invention, the section being taken on line 1—1 of Fig. 2, and 35

Fig. 2 is a sectional view thereof taken substantially on line 2—2 of Fig. 1.

The form of our invention illustrated in the drawing comprises a table structure provided with a heating platform or top plate 11, which is preferably constructed of metal, and is re-enforced adjacent its outer edges by means of bars 12 and is supported by suitable legs 13. A drain or gutter 14 is 40 formed at the outer edges of the top plate 11 and an outlet duct 15 leads downward from said drain. A chamber 16, V-shaped in cross section, is provided beneath the top plate 11 and the bottom of which comprises 45 a sheet of metal having its edge portions 17 set in recesses formed in the bars 12 and firmly engaging beneath the top plate forming a steam-tight chamber therewith. The inwardly and downwardly slanting walls 50 18 are provided with a narrow bottom 18',

as shown in the drawing. A pair of ducts 19 extend downwardly from the ends of the bottom 18', each communicating with a cylindrical housing 20 which has a threaded opening 21 at one end, in which is threaded 60 a plug 22 having an angular head 23 to afford ready removal of the plug, said housings having a fluid connection through an intermediate pipe 20'. The plug 22 carries heating means 24, diagrammatically shown, 65 said heating means being connected in circuit with a suitable source of electric energy 25 by means of conductors 26, and said conductors are preferably connected in circuit with the heating means by the use of an 70 ordinary wall plug indicated at 27.

A platform 28 is connected to one side of the legs 13 by means of brackets 29, and supports the receptacle 30 beneath the outlet duct 15 for receiving the melted wax therefrom. 75

A pipe 31 extends outwardly and upwardly from chamber 16 and is provided with a removable steam gauge 32 at its upper end, the steam gauge serving to register the 80 pressure of the steam within the chamber 16.

The platform or top plate 11 is heated for removing wax from the copper impression plate (not shown) after an impression has been taken from a printer's plate (not 85 shown) in the following manner. Water is admitted into the ducts 19 either through the pipe 31 by removing gauge 32, or through the openings 21 on housings 20, the level of the water being placed slightly above the 90 connection between pipe 19 with its housing 20, as indicated by line 33 in Fig. 1, the gauge 32 being replaced on the pipe after the desired amount of water has been provided in the housings 20. The electric means 95 24 is then made operative and the water in the housings heated and generated into steam which rises through the ducts 19 into chamber 16, the pressure of the steam being registered by the steam gauge. The air 100 is then excluded or driven from the apparatus by removing the gauge, permitting the steam to force the air out of the ducts 19, chamber 16 and pipe 31, the gauge being replaced when steam issues from the pipe, 105 to retain the steam within the chamber. The platform or top is thus heated by the steam and melts the wax from the copper impression plate, which wax will flow through the drain 14 and duct 15 into the receptacle 30 to be 110

retained and remelted therein. When the wax has been melted from the impression plate the electric heating means is rendered inoperative, and the steam will cool and be 5 condensed into water being retained in the housings 20.

While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within 10 the scope of the appended claims.

Having described our invention, what we claim as new and desire to secure by Letters Patent is:

20 1. An apparatus of the class described comprising a supporting plate provided with a steam-tight chamber therebeneath and a duct extending from said chamber, a housing at the lower end of said duct for containing water, heating means extending into the housing for heating the water to generate steam, said steam being adapted to pass through the duct and into the chamber to heat said plate, and a pipe communicating 25 with said chamber and carrying a removable gauge at its outer end, said gauge being removable to permit the removal of air from said chamber by means of said steam and to be replaced for retaining said steam with- 30 in said chamber.

2. An apparatus of the class described comprising a level top plate provided with a chamber thereunder, a drain provided around the outer edge of said plate and having an outlet duct extending therefrom, a duct extending from said chamber, a housing at the lower end of said duct for containing a quantity of water, electric heating means extending into said housing for heating 40 the water to generate steam to pass into said chamber and heat said plate, and a pipe on said chamber with a steam gage which is 45

removable for escape of air from said chamber and is replaceable to retain the steam in 50 said chamber.

3. An apparatus of the class described comprising a table construction provided with a metal top plate having a drain formed around its outer edge, a drain duct extending downward from said drain, a shelf on said table for supporting a receptacle beneath said drain, a chamber formed beneath said plate by means of a V-shaped construction fastened beneath said plate, a pair of ducts extending from the bottom of 55 said chamber, a housing at the lower end of each duct for containing water, and electric heating means in each housing for heating the water and generating steam therewith, 60 said steam passing through said ducts into said chamber for heating said plate.

4. An apparatus for melting wax from an impression plate, and comprising a table construction provided with a metal top plate having a drain formed around its outer edge, an outlet duct extending downward from said drain, a plate substantially V-shaped in cross section fastened beneath said top plate and forming a chamber therewith, a pair of ducts extending from the 70 bottom of said chamber, a housing at the lower end of each duct for containing water, a threaded plug in one end of each housing, electric heating means carried by each of 75 said threaded plugs and extending into its housing for heating the water therein to generate steam for heating said top plate, and a pipe on said chamber with a steam gage which is removable for escape of air from 80 said chamber and is replaceable to retain the steam in said chamber.

In testimony whereof we have signed our names to this specification in the presence of two subscribing witnesses.

OSCAR C. BAER.
ROBERT L. WHEAT.
